(57) **CLAIM**

The ornamental design for an exercise board, as shown and described.

DESCRIPTION

FIG. 1 is a front and right side perspective view of an exercise board illustrating my new design;

FIG. 2 is a top view thereof;

FIG. 3 is a bottom view thereof;

FIG. 4 is a front view thereof;

FIG. 5 is a back view thereof;

FIG. 6 is a right side view thereof; and,

FIG. 7 is a left side view thereof.

The broken line showing of portions of the exercise board depicts environment and forms no part of the claim.

1 Claim, 5 Drawing Sheets
